(57) **CLAIM**

The ornamental design for a chip connector, as shown and described.

DESCRIPTION

FIG. 1 is a perspective view of a chip connector showing our new design;

FIG. 2 is a front elevational view thereof; and,

FIG. 3 is an enlarged partial front elevational view cut along the line 3-3 of FIG. 2.

The broken lines illustrating chip connector portions are unclaimed portions thereof and form no part of the claimed design. The dot-dash broken lines define the boundaries of, but are not included in, the claimed design.
